US0D1074544S

(12) **United States Design Patent** (10) **Patent No.:** **US D1,074,544 S**
(45) **Date of Patent:** **** May 13, 2025**

(54) **AIR INTAKE ASSEMBLY**

(71) Applicant: **Volvo Truck Corporation**, Gothenburg (SE)

(72) Inventor: **Alexandre Henriques**, Greensboro, NC (US)

(73) Assignee: **Volvo Truck Corporation**, Gothenburg (SE)

(**) Term: **15 Years**

(21) Appl. No.: **29/901,464**

(22) Filed: **Sep. 1, 2023**

(51) **LOC (15) Cl.** **12-16**

(52) **U.S. Cl.**

USPC **D12/163**

(58) **Field of Classification Search**

USPC D8/322; D12/162, 163, 171, 172, 181, D12/190, 195, 196, 203, 414, 416

(57) **CLAIM**

The ornamental design for an air intake assembly, as shown and described.

DESCRIPTION

FIG. 1 is a front, right, top perspective view of an air intake assembly showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

A second embodiment of the claimed design for the air intake assembly is a mirror image of the air intake assembly as shown in FIGS. 1 to 7.

1 Claim, 4 Drawing Sheets
